UNITED STATES PATENT OFFICE.

OTTO WIEDEKE, OF DAYTON, OHIO, ASSIGNOR OF ONE-HALF TO GUSTAV WIEDEKE, OF DAYTON, OHIO.

TUBE-EXPANDER.

1,153,662.

Specification of Letters Patent. Patented Sept. 14, 1915.

Application filed December 12, 1914. Serial No. 876,930.

To all whom it may concern:

Be it known that I, OTTO WIEDEKE, a citizen of the United States, residing at Dayton, in the county of Montgomery and State 5 of Ohio, have invented certain new and useful Improvements in Tube-Expanders; and I do declare the following to be a full, clear, and exact description of the invention, such as will enable others skilled in the art to 10 which it appertains to make and use the same, reference being had to the accompanying drawings, and to the letters and figures of reference marked thereon, which form a part of this specification.

15 This invention relates to certain new and useful improvements in boiler tube expanders with a special adaptation for bellng the end of a tube where it joins the tube sheet or head, as in fixing the end of the tube in 20 the aperture in the tube sheet or head.

In carrying out the purposes of the invention, I employ two expanding rollers, one a roller of uniform diameter and the other a roller of tapered periphery. These 25 rollers each having their particular function to perform, are mounted upon a common axial support and are free to move independently of each other, as will herein-after more fully appear. The tool is inserti- 30 ble in the end of the tube which is placed in the aperture therefor in the tube sheet or head, the expanding roller of uniform diameter being in a position to properly expand the tube against the surrounding surface of 35 the said tube sheet and the other roller, to-wit, the tapered roller being in a position to bell or bend outwardly the end of said tube on the outside of the tube sheet.

40 A further object of my invention is to provide a reversible guard and support therefor by means of which the insertion of the tool is gaged to meet different requirements. In carrying out the latter purpose, I provide the roller cage with a tubular ex- 45 tension exteriorly screw-threaded and a correspondingly interiorly screw-threaded sleeve upon which the guard is mounted, the sleeve being insertible in reversed positions on the said screw-threaded extension, as will 50 hereinafter more fully appear from the following description in connection with the accompanying drawings.

Referring to said drawings, Figure 1 is a horizontal longitudinal section of my im-

proved boiler tube expander showing the 55 same in position in a nipple or tube; Fig. 2 is a sectional view on the line *a—a* of Fig. 1; Fig. 3 is a section on the line *b—b* of Fig. 1; Fig. 4 is a horizontal elevation of the tube expander showing the guard reversed from 60 the position shown in Fig. 1 and with a portion of the mandrel broken off; Fig. 5 is a sectional view of the expanding rollers removed from the cage.

In a detail description of the invention, 65 similar reference characters indicate corresponding parts in the several views of the drawings.

The roller cage or frame 1 has the necessary number of pockets 2 for housing the expanding rollers in the usual manner. A tubular extension 3 extends from the cage through which the mandrel 4 extends. The tubular extension 3 has exterior screw- 70 threads 5 which are engaged by similar internal threads 6, on an adjusting sleeve or collar 7. A slot 8 extends longitudinally in the exterior service of the cage extension 3 and receives the end of a screw 9 which penetrates an opening in the collar 7 and by 75 means thereof the collar 7 is prevented from rotating on the extension 3. The collar 7 has an annular groove or recess 10 in the periphery thereof, in which is rotatably mounted a guard-ring 11. It will thus be 80 seen that the position of the guard-ring 11 may be reversed to bring one or the other face thereof to a position to gage or limit the insertion of the tool in the tube. As appears in Fig. 1, the annular shoulder or face 85 90 on the guard is engaged by the end of the nipple or pipe 12, while in Fig. 4, the extreme end of the said guard is in a position to engage that portion of the tube. The nipple or tube is shown in Fig. 1 with an end 95 projected through the tube aperture in the tube sheet or head 13. The end of the said tube is there shown to be expanded annularly against the surrounding surface of the aperture therein, while the extreme end of 100 said tube is expanded to a greater extent or flared outwardly on one side of said tube sheet. This manner of uniting the end of the tube to the tube sheet is performed by two distinct forms of expanding rollers 14 105 and 15 which are mounted together on a single axial support or pin 16. The roller 14 is of substantially uniform diameter and is

instrumental in expanding the tube uniformly while roller 15 is tapered and designed to bell the extreme end of the tube.

In order that the belling or tapered roller 15 shall have a necessarily greater extent of lateral movement, the axial opening therein is greater on one side and gradually decreases in size so that said roller will be free to receive the necessary movement and yet 10 will be retained at all times in an operative position upon the pin 16 with roller 14. The face 17 of roller 14 adjacent to the belling roller 15 is of convex form in order to permit the said roller 15 to present a parallel surface to the mandrel and to provide a proper bearing for said roller 15, when the latter is being forced outwardly by the mandrel. As the mandrel is inserted in the opening it engages the surfaces of the two 15 rollers substantially in the positions in which they are shown in Fig. 5 and as said mandrel is forced in the inner surface of the belling roller 15 assumes a position in a plane with the surface of the roller 14, thus increasing the inclination of the outer side of said roller 15 with reference to the plane of the boiler tube. The roller pockets 2 each open into a longitudinal space 2' in which retaining pins 18 lie and serve to prevent the rollers dropping into the mandrel opening when the mandrel is removed.

While I have with some particularity described my improved tool in order to meet the requirements of section 4886 of the Revised Statutes, I do not wish to be limited to all of the precise details of construction herein shown and described, as it will be apparent to those skilled in the art that certain modifications and variations may be made without departing from the essentials of the invention. For example, while I deem it important that the belling roller and the roller of uniform diameter shall be mounted on a common axial support and thus be inseparably maintained, this axial support may vary to some extent in its form and, too, the roller cage or frame may be varied in size and possibly in shape without departing from the invention.

Having described my invention, I claim.

1. In a tube expander, the combination

with a roller cage, of an expanding roller of uniform diameter, and a tapered expanding roller, the axial opening in the tapered roller being of greater area than that of the 55 roller of uniform diameter, a common axial support for said rollers, and a mandrel engaging said rollers to expand a tube and bell the end thereof, substantially as specified.

2. In a tube expander, the combination with a roller cage, of an expanding roller of uniform diameter provided with a convex face, a tapered roller having an enlarged axial opening therein, a pin upon which 65 both rollers are mounted and maintained, the tapered roller having a greater extent of movement owing to its greater axial opening, and a mandrel engaging said rollers, substantially as described.

3. In a tube expander, the combination with a roller cage, of expanders mounted upon a common pin, one of said rollers being of tapered form and the opening in the axis thereof being increased outwardly 75 whereby said roller may have greater lateral movement on said pin when forced outwardly, and a mandrel engaging said rollers, substantially as described.

4. In a tube expander, the combination 80 with a roller cage having an exteriorly screw-threaded extension provided with a longitudinal groove in the exterior surface of said extension, an interiorly screw-threaded collar engaging said extension, a 85 guard supported on said collar, and a screw penetrating said collar and entering the longitudinal groove in said extension, of an expanding roller of uniform diameter, and a tapered roller mounted in said cage in 90 alinement one with the other, said rollers being both mounted upon a common pin and said tapered roller having its axial opening of gradually increasing diameter, substantially as specified.

In testimony whereof I affix my signature, in presence of two witnesses.

OTTO WIEDEKE.
